UNITED STATES PATENT OFFICE.

CHARLES WESTMAN, OF HINCKLEY, MINNESOTA.

FOOT-REST.

1,231,107.

Specification of Letters Patent. Patented June 26, 1917.

Application filed September 7, 1916. Serial No. 118,892.

To all whom it may concern:

Be it known that I, CHARLES WESTMAN, a citizen of the United States, residing at Hinckley, in the county of Pine and State 5 of Minnesota, have invented certain new and useful Improvements in Foot-Rests, of which the following is a specification.

This invention relates to foot supports, and is adapted particularly for use upon radiators of steam or hot water heating systems.

The primary object of the invention is to provide a simple and efficient foot rest which is capable of being easily and quickly attached to and detached from the well known types of heat radiators, which is capable of being adjusted to the desired height and angularity, and which may be swung out of position when not in use to occupy but little 20 space and not to prove unsightly in the room.

A further object of the invention is to provide a foot rest of this character which is of inexpensive construction, which is composed of a few simple, durable and readily 25 assembled parts, all of which are so arranged and assembled as to prevent wear, breakage or derangement of the same, which is capable of being folded or collapsed so as to occupy but a small amount of space, and 30 which will prove thoroughly efficient in the attainment of the ends for which it is designed.

With these objects in view, together with others which will appear as the description 35 proceeds, the invention resides in the novel formation, combination and arrangement of parts as will be described more fully hereinafter, illustrated in the drawings, and particularly pointed out in the claims.

40 The invention will be best understood with reference to the accompanying drawings, wherein:

Figure 1 is a top plan view of a conventional form of steam or hot water radiator 45 and illustrating the application of a foot rest constructed in accordance with my invention, and

Fig. 2 is a fragmentary end elevation of a radiator and the improved foot rest.

50 Referring now more particularly to the drawings, 3 represents generally the radiator, which is composed of a plurality of communicating vertically disposed spaced coils. The radiator in the present instance 55 is of that type wherein a double set of coils are employed, and it will be understood

from the following description that the device may with equal facility be applied to any of the well known types of heat radiators.

60

The main support for the attachment comprises a relatively long rod 5 of a length slightly greater than that of the radiator to which the device is applied. This rod is threaded at its extremities as shown, and is 65 adapted for insertion between the coils of the radiator. When thus inserted through the radiator coils it is apparent that the rod is capable of being moved vertically, and to maintain the rod in its various positions of 70 adjustment, clamp members 6 are engaged over the extremities of the said rod. These clamp members comprise laterally extending arms 7, which are adapted to engage around the radiator coils to embrace the same, and wing nuts 8 may be threadedly engaged with 75 the extremities of the rod 5 to bind the said clamp members against the end coils of the radiator.

A second rod or support 9 is associated 80 with the rod 5 for supporting the foot rest. This rod also has its extremities threaded, and is adapted to receive the clamping members 6 for engagement with the outer coils 85 of the radiator. The wing nuts 10 are engaged with the extremities of the said rod 9 to firmly bind the same to the radiator coils.

The foot rest is indicated at 11, and comprises an elongated rectangular plate constructed preferably of metal, and which has spaced outwardly projecting ears 12 upon its opposite longitudinal edges. The supporting rods 5 and 9 are hingedly connected 90 with the platform 11 by links 13, the latter being pivoted at their innermost ends between the ears 12, and being loosely engaged at their outer extremities over the rods 5 and 9. This construction permits of the foot supporting platform 11 being adjusted to 100 various degrees of inclination. By fastening the rod 9 adjacent the base portion of the radiator and adjusting the main support 5 above the same, the inclination of the platform may be regulated. From this description it is apparent that I have provided 105

an extremely simple and yet thoroughly efficient radiator foot rest, and one which may be quickly and easily attached to or detached from radiators of the type now generally in use. The rod 5 may be inserted 110 through the radiator coils and through the

links 13 extending therebetween and the clamps and binding nuts at the extremities of the said rod will firmly support the same upon the radiator coils. While the above 5 is a description of the preferred embodiment of the invention, it is apparent that various changes in the minor details of construction and arrangement of parts may be resorted to if desired without departing 10 from the spirit of the invention or exceeding the scope of the claims.

What is claimed is:—

1. In a foot rest for radiators, a main support comprising a rod adjustably 15 mounted upon the radiator, a second rod mounted for adjustment upon the radiator, a platform member, and links connecting said platform member and said rods, substantially as described.
- 20 2. In a foot rest for radiators, a rod adapted to extend longitudinally of the radiator and through the coils thereof, a second rod mounted upon the exterior of the radiator, clamp members on the extremities 25 of said rods for engagement with the radiator coils, means for clamping said clamps upon said coils, and a platform pivoted between said rods, substantially as described.
3. In a foot rest for radiators, a rod 30 adapted to extend longitudinally of and between the coils of a radiator, a second rod arranged upon the exterior of said radiator, threads on the ends of said rods, clamping members on said rod ends adapted to engage 35 with the coils of the radiator, nuts for engagement with the threaded ends of said rods to bind said clamps into engagement

with the coils of said radiator, a platform, spaced laterally projecting ears on said platform, and links pivoted between said ears 40 at their inner ends and being pivoted at their opposite ends to said rods, substantially as described.

4. In a foot rest for radiators, a main support mounted for sliding movement 45 upon the radiator, means for holding said support against movement, a second support slidably mounted on said radiator, means for holding said second support against movement, a platform, and links connecting 50 said supports and said platform, substantially as described.

5. In a foot rest for radiators, a main support comprising a rod, clamp members 55 slidably mounted on said rod, means for forcing said clamp members longitudinally of said rod, a second support comprising a rod, clamp members slidably mounted on said rod, means for forcing said members longitudinally of said rod, a platform, and 60 links connecting said platform, substantially as described.

6. In a foot rest for radiators, a pair of supports capable of moving vertically upon a radiator, means for holding said supports 65 in adjusted position, a platform, and links connecting said platform and said supports, substantially as described.

In testimony whereof I affix my signature in presence of two witnesses.

CHARLES WESTMAN.
